UNITED STATES PATENT OFFICE.

CHARLES J. MENASCO, OF BIRMINGHAM, ALABAMA, ASSIGNOR OF ONE-HALF TO
HOWARD A. MOSELEY, OF BIRMINGHAM, ALABAMA.

INTERNAL-COMBUSTION ENGINE.

1,270,481.

Specification of Letters Patent. Patented June 25, 1918.

Application filed January 10, 1917. Serial No. 141,682.

To all whom it may concern:

Be it known that I, CHARLES J. MENASCO, a citizen of the United States, and a resident of Birmingham, in the county of Jefferson and State of Alabama, have invented a certain new and useful Improvement in Internal-Combustion Engines, of which the following is a specification.

My present invention relates generally to internal combustion engines, and more particularly to certain improvements applied in particular in connection with that type of engine including opposed pistons, an object of my improvements being the provision of an engine having means to prevent pressure and power loss in the exhaust ordinarily resulting from but partial expansion of the gases in the usual engine cylinder whose cubic area of expansion will not permit of complete expansion of the gases before they are exhausted.

A further object of my invention is to provide an engine construction including means whereby to fully utilize, take up, and transmit the full force of the expansion of the gases at the moment of explosion, and to transmit the same to a power shaft in such manner as to take much higher maximum leverage with minimum strain upon the driven and connecting parts.

A still further object of the invention is to provide an internal combustion engine of the opposed piston type having novel and effective connections between the pistons, and a power shaft including means by which the pistons are moved in one direction, and one of the pistons controlled during each cycle of operation between the explosions.

With these and other objects, residing for the most part in the means employed in carrying out the above, my invention resides in the features of construction, arrangement and operation to be now described with respect to the accompanying drawings forming a part of this application, and wherein—

Figure 1 is a vertical sectional view through my improved engine;

Fig. 2 is a view partly in elevation and partly in vertical section, taken substantially on line 2—2 of Fig. 1;

Fig. 3 is a view similar to Fig. 2, taken substantially on line 3—3 of Fig. 1;

Figs. 4 to 8 inclusive are diagrammatic views illustrating the several cycles of operation of the engine shown in Fig. 1.

Referring now to these figures, and particularly to Fig. 1, my invention contemplates the provision of an engine cylinder 15, in the present instance, disposed vertically, as clearly seen, and open at both ends, 60 with opposing upper and lower pistons 16 and 17, the inner ends of the connecting rods of which are threaded into the pistons, as seen at 18, and locked in connection therewith by lock nuts 19. 65

The cylinder 15 so disposed is mounted upon a bed plate 20, with its lower open end above an opening 21 in the said bed plate, which latter is supported in elevated position by its depending sides 22, as seen in Figs. 2 70 and 3, and held at such height as to readily accommodate a crank case 24 beneath the bed plate.

The depending connecting rod 25 of the lower piston 17 projects through the opening 21 of the bed plate just above mentioned, and is provided at its lower extremity within the crank case with brackets 26 through which is extended a horizontally disposed pin 27 whose axis is at right angles to the 75 axis of the connecting rod 25, and upon which are mounted rollers 28, 29, and 30, the bracket having at one side a depending extension 31 at the lower end of which is a laterally projecting pin 32 having thereon 80 a roller 33.

The upwardly projecting connecting rod 34 of the upper piston 16 extends downwardly at the outside of the cylinder 15, as seen in Fig. 2, and is provided at its lower 85 outer end with an inwardly bent extension 35 having a bracket 36 thereon, as seen in Fig. 1, provided with a horizontal pin 37 disposed at right angles to the axis of the rod 34, and on which are journaled a plurality of rollers 38, 39, 40, and 41, the bracket 36 being somewhat similar in shape to the bracket 26 of the connecting rod 25 and having at one side thereof opposite to the extension 31 of the bracket 26, an upwardly projecting side extension 42, at the upper end of which is a laterally projecting pin 43 on which is a roller 44.

A power shaft 45 is journaled through bearings in the ends of the crank case 24, 105 and also through bearings in the lower portions of extensions 46 depending from one side of the bed plate 20 within the crank case; and is provided at a central point with an elliptical cam 47 engaged at rela- 110

tively opposite sides by the rollers 29 and 40 of the brackets 26 and 36. Journalized upon the shaft 45 at relatively opposite sides of its central cam 47 are sleeves 48 and 49, the former of which is provided with an elliptical cam 50 engaged at relatively opposite sides by rollers 28 and 39 of the brackets 26 and 36, and the latter of which is provided with an elliptical cam 51 engaged at its relatively opposite sides by the rollers 30 and 41 of the brackets 26 and 36, all as clearly seen in Fig. 1. It will be noted that the rollers 29 and 40 engage relatively opposite faces of the cam 47 as compared to the engagement of the rollers 28, 39, 30, and 41 with the cams 50 and 51, as seen by a comparison of Figs. 2 and 3, so that in the relative reciprocating movements of the brackets 26 and 36 with respect to one another the operation of the engine, as hereinafter described is accomplished. The rollers of the two brackets work between the cam 47 on the one hand and the cams 50 and 51 on the other hand, and thus effect rotation of the shaft 45 in a direction relatively opposite to that of the rotation imparted to the sleeves 48 and 49.

The sleeves 48 and 49 are further provided at their outer ends with bevel gears 52 and 53 respectively in mesh with bevel gears 54 and 55 journalized at the lower end of the bearing posts 46, and the latter of which are in turn in mesh with bevel gears 56 and 57 at spaced points, so as to thus rotatably couple the shaft 45 to the sleeves 48 and 49 so as to communicate to the shaft the power transmitted to the cams 50 and 51 as well as the cam 47 secured directly to the shaft. The remaining roller 38 of the bracket 36 in the upper piston 16, engages a substantially half round cam 58, secured upon the sleeve 48 for a purpose which will be presently explained in treating of the control of the upper piston 16 during each cycle of operation of the engine.

Each of the extensions 31 and 42 of brackets 26 and 36 is slotted, as seen by reference to Figs. 2 and 3, to receive the shaft 45 and the sleeves 48 and 49, the roller 33 of extension 31 engaging a butterfly cam 59 secured upon the sleeve 49, and the roller 44 of extension 42 engaging a wing shaped cam 60 carried by the sleeve 48.

Thus, in the operation of the motor in so far as the parts above described are concerned, and with these parts in position at the start of the power stroke, as seen in Fig. 1 and in the diagram Fig. 4, the force of the expanding fluid between the pistons 16 and 17 will cause the latter to move apart, the former upwardly, and the latter downwardly. Thus, the rollers 28, 29, and 30 of the lower piston and the rollers 39, 40, and 41 of the upper piston will move in relatively opposite directions toward one an-

other and toward the power shaft 45, between the shaft driving cams 50, 47, and 51, forcing the cam 47 in one direction and the cams 50 and 51 in the other direction, through the connections between the sleeves 48 and 49 and the power shaft 45, causing movement of the power shaft in one direction. In this manner, the full force of the exploded gases at the instant of explosion, is applied to the rotation of the power shaft, with considerably greater leverage than is possible with the crank and pitman usually in use for this purpose, and, furthermore, this power is applied to the power shaft in such manner as to eliminate torsional stresses and strain and balance the same at all times.

The advantages accruing from this arrangement of cams for the operation thus consists in conserving and converting all of the elements of power from the cylinder and applying the same to the crank shaft in such manner as to derive the greatest benefit therefrom and a greater benefit than can possibly be derived through the usual crank and pitman connections. In Fig. 2 the cams are shown with the rollers just starting between them at both ends wedgewise, and this action occurs practically at the instant of, and not after, combustion has taken place, so as to thereby exert the maximum force against the maximum leverage, which force and leverage decrease uniformly to the end of the power stroke.

The power stroke thus brings the pistons 16 and 17 to their outermost positions, as shown in the diagram Fig. 5, ready for the exhaust stroke, at which point the rollers 28, 29, 30, 39, 40, and 41, have arrived at the minor axis of the cams 47, 50 and 51, and said cams continuing to rotate, the ends opposite the beginning of the power stroke begin to come together, in a scissors-like action, squeezing the rollers 28, 29, 30, 39, 40, and 41 out to the cams major axis, rollers 28, 29, 30, carrying their bracket 26, connecting rod 25, and piston 17 upward to its inner position, rollers 39, 40, 41, carrying their bracket 36, connecting rod 34, and piston 16, downward to its inner position, thus completing the exhaust stroke. At the end of the exhaust stroke, the parts will be in the position shown in Fig. 6, with the pistons 16 and 17 at the limits of their inward travel toward one another, and at this point the upper piston 16 is held by virtue of the engagement of the half round cam 58 with its roller 38, so as to maintain the same in the position shown in the diagram Fig. 7, while the lower piston 17 is forced downwardly by the opposite side of its butterfly cam 59, on the suction stroke, the scissors-like action of cams 47, 50, and 51, squeezing rollers 28, 29 and 30 out, causing upward movement of the lower piston 17 to the position shown in Fig. 8, during the compression

stroke, and thus again bringing the parts into position ready for explosion.

Should the charge fail for any reason to be exploded, the regular cycle of operations will still be proceeded with as before described, except that the cam 60 before referred to as engaging the roller 44 of the bracket extension 42, will lift the upper piston 16 and thus maintain its bracket rollers in uniform contact with the operating cams 47, 50, and 51.

The shaft 45 at one end, beyond one end of the crank case 24, is preferably provided with the usual balance wheel 60^a, and, as shown in Fig. 1, the cylinder 15 is provided at opposite sides of its central point, with laterally opening intake and exhaust ports 61 and 62, in casings 63 and 64, respectively communicating with the intake and exhaust manifolds 65 and 66, through valves 67 and 68 seated in the lower portions of the casings 63 and 64, with their depending stems 69 and 70 normally held in lowermost position by springs 71 and 72. The stems 69 and 70 depend through guide openings in the bed plate 20, as seen at 73 in Fig. 1, and the lower extremities of the stems are provided with rollers 74 and 75 with which cam tappets 76 and 77, respectively secured to the sleeves 49 and 48, engage, so as to lift the valves 67 and 68 at the proper time.

In the upper portion of each of the intake and exhaust casings 63 and 64, is threaded an enlarged cover 78, by removal of which ready access may be had to the valves 67 and 68, and through these covers 78, are threaded spark plugs 79, the leads 80 of which extend to a stationary contact member 81 secured upon the upper surface of the bed plate 20, as shown in Fig. 1, above the upper end of a movable vertically disposed contact rod 82, having a roller 83 at its lower end for engagement with a cam tappet 84 which, at the proper time, elevates the contact rod 82 into contact with the stationary member 81, and thus closes the circuit of the spark plugs, so that sparks will be supplied at both sides of the combustion space, and effective ignition of the charge secured, it being noted that the timer is fixed in the present instance, so that the explosion will always occur in properly timed relation with respect to the position of the bracket rollers in connection with the cams 47, 50, and 51.

The lower portion of the crank case 24 forms a storage space for lubricating oil, and within the lower portion of said crank case is disposed a small oil pump including a cylinder 85 having an intake 86 opening into the lower portion of the crank case, and an outlet connected with an oil supply pipe 87, the piston 88 of the pump having its stem 89, as seen in Fig. 1, connected with an eccentric 90 actuated by the sleeve 49, in order that a continuous supply of oil will be

forced outwardly through the oil supply pipe 87 during operation of the motor. The upper end of the oil supply pipe 87 extends around the cylinder 15, and communicates therewith by means of a plurality of 70 branches 91, as seen in Fig. 1, which branches are let into the cylinder 15 in a horizontal plane at a point between the limits of upward and downward movement of the upper piston 16, so that the branches 91 will be 75 closed by the upper piston at all times, allowing only sufficient oil to enter the cylinder to lubricate the upper piston 16, the lower piston 17 being lubricated by the splash from the crank case 24. The oil returns to the crank case through an oil return pipe 92, which is preferably provided with a cut-off valve 93, as seen in Fig. 1, in order that the back flow of oil may be considerably checked, and pressure of the oil increased in the branches 85 91 to the cylinder 15, to force the same against the surface of the piston 16 at all times.

Referring again to Figs. 1 and 2, and particularly to the latter, I provide improved air cooling means, consisting of a radiator casing 100 which completely surrounds the cylinder, and seats upon the bed plate 20, spring catches 101, as seen particularly in Fig. 2, being utilized for the purpose of holding this casing in position. The casing 100 so disposed, is open at one end for the reception of air currents from a suitable fan, not shown, and the casing is otherwise closed except for an opening 102 in its top 100 103, located above cylinder.

Thus, with these features and those before described, it may be readily seen that I provide an improved motor of the type, and for the purpose set forth, which will be effective 105 and efficient in use, economical in upkeep, durable, and one readily capable of carrying out the objects first above mentioned.

I claim:

1. In an internal combustion engine, the 110 combination of a working cylinder, opposed pistons therein, having depending piston rods, brackets carried by said rods and movable toward and away from one another, a power shaft between said brackets, a cam secured to said shaft at an intermediate point, a pair of sleeves rotatable upon said shaft at opposite sides of said cam, and having geared connections with the shaft, a cam carried by each sleeve, rollers carried by said brackets 115 and engaging relatively opposite sides of said shaft and sleeve cams, and means carried by said sleeves for moving the pistons in one direction and controlling the same in such movement.

2. In an internal combustion engine, the 120 combination of a working cylinder, opposed pistons therein, having depending piston rods, brackets carried by said rods and movable toward and away from one another, a 125

130

power shaft between said brackets, a cam secured to said shaft at an intermediate point, a pair of sleeves rotatable upon said shaft at opposite sides of said cam, and having 5 geared connections with the shaft, a cam carried by each sleeve, rollers carried by said brackets and engaging relatively opposite sides of said shaft and sleeve cams, cams carried by said sleeves for moving said pistons 10 in one direction, and means for checking movement of one of said pistons during a portion of each cycle of movement of the other piston.

3. In an internal combustion engine, the 15 combination of a working cylinder, opposed pistons therein having depending piston rods, brackets carried by said rods and movable toward and away from one another, a power shaft between said brackets, a cam 20 secured to said shaft at an intermediate point, a pair of sleeves rotatable upon said shaft at opposite sides of said cam, and having geared connections with the shaft, a cam carried by each sleeve, rollers carried by said 25 brackets and engaging relatively opposite sides of said shaft and sleeve cams, cams carried by said sleeves for moving said pistons in one direction, a cam carried by one of said sleeves for checking movement of one 30 of said pistons during a portion of each cycle of movement of the other piston, and rollers carried by said brackets and engaging said last mentioned sleeve cams.

4. In an internal combustion engine, the 35 combination of a working cylinder, opposed pistons therein, having depending piston rods, brackets carried by said rods and movable toward and away from one another, a power shaft between said brackets, a cam 40 secured to said shaft at an intermediate point, a pair of sleeves rotatable upon said shaft at opposite sides of said cam and having geared connections with the shaft, a cam carried by each of said sleeves, rollers carried 45 by said brackets and engaging said shaft and sleeve cams, cams carried by said sleeves for moving said pistons in one direction, a cam carried by one of said sleeves for controlling movement of one of said 50 pistons, and rollers carried by said brackets and engaging said last mentioned sleeve cams.

5. In an internal combustion engine, the 55 combination of a working cylinder, opposed pistons therein, a power shaft, and connections between said pistons and said power

shaft, including piston actuated cams connected to the power shaft, piston returning cams also connected to the power shaft, and means for checking movement of one of said 60 pistons during a portion of each cycle of movement of the other piston.

6. In an internal combustion engine, the combination of a working cylinder, opposed 65 pistons therein, a power shaft, and connections between said pistons and said power shaft including piston actuated cams carried by the power shaft, certain of which are secured to said shaft, and sleeves on the shaft to which the other cams are connected, 70 having geared connection with the shaft.

7. In an internal combustion engine, the combination of a working cylinder, opposed pistons therein, a power shaft, sleeves rotatable on the shaft and geared thereto, a 75 piston actuated cam secured to the shaft between said sleeves, piston actuated cams secured on the sleeves at opposite sides of the shaft cam, and cam actuating rollers carried by and movable with the said pistons, and 80 extending between the said shaft and sleeve cams.

8. In an internal combustion engine, the combination with a working cylinder, opposed 85 pistons therein, a power shaft, a pair of cams geared to the power shaft, a cam secured to the shaft and movable in a direction opposite to the first cams, and cam actuating means carried by and movable with the said pistons and extending between 90 the said first and second cams.

9. In an internal combustion engine, the combination of a working cylinder, a piston therein, a power shaft, a pair of cams rotatable on and geared to the said power 95 shaft, a cam secured to the power shaft between said first named cams, and movable in a direction opposite thereto, and cam actuating means carried by said piston and movable between the said first and second 100 cams.

10. In an internal combustion engine, the combination of a working cylinder, opposed pistons therein, a power shaft, cams connected to the power shaft, and rollers engaging said cams and movable with said pistons toward and away from the power shaft at diametrically opposite sides of said shaft.

CHARLES J. MENASCO.
